UNITED STATES PATENT OFFICE.

JOHN F. FIETSCH, OF FOREST PARK, ILLINOIS.

DEVICE FOR MEASURING MATERIAL FOR TOOTH-FILLINGS.

1,353,467.

Specification of Letters Patent. Patented Sept. 21, 1920.

Application filed June 25, 1916. Serial No. 104,830.

To all whom it may concern:

Be it known that I, JOHN F. FIETSCH, a citizen of the United States, residing at Forest Park, in the county of Cook and State of Illinois, have invented a certain new and useful Improvement in Devices for Measuring Material for Tooth-Fillings, of which the following is a specification.

This invention relates to devices for measuring materials for tooth fillings, and has for its object to provide a new and improved device of this description. In forming amalgam fillings, for example, from powdered metal and mercury, it is essential to secure a filling of the proper lasting qualities, to mix powdered metal and mercury in certain definite proportions. It is usual among dentists at the present time to guess at the amount at the time the filling is made. This method is objectionable, as it is practically impossible to secure the proper proportions in this manner. One of the objects of my invention is to provide a device by means of which the proper proportions of powdered metal and mercury may be easily and quickly obtained at the time the filling is being inserted, and by means of which the proper amounts may be easily provided without waste of material.

The invention is illustrated in the accompanying drawings, wherein—

Figure 1 is a view showing one form of device embodying the invention;

Fig. 2 is a sectional view taken on line 2—2 of Fig. 1;

Fig. 3 is an enlarged longitudinal sectional view of a portion of one of the rotatable parts.

Fig. 4 is a sectional view taken upon the line 4—4 of Fig. 1;

Fig. 5 is a plan view of the agitating plate;

Fig. 6 is a sectional view taken on line 6—6 of Fig. 5.

Fig. 7 is a view of a portion of one of the rotatable parts showing permanent measuring openings.

Like numerals refer to like parts throughout the several figures.

In carrying out my invention, I provide a body portion 1, of any suitable material such, for example, as glass, hard rubber or the like. This body portion is preferably integral and is provided with two receptacles 2 and 3. The receptacle 2 is for the

mercury and the receptacle 3 for the powdered material. These receptacles are provided with covers 4 and 5, which are preferably screw-threaded, the upper ends of the receptacles being screw-threaded to receive the covers. Below the receptacles 2 and 3 are the rotatable parts 6 and 7, which extend through holes 8 and 9 in the body portion 1, said holes communicating with the receptacles 2 and 3. The rotatable parts 6 and 7 are provided with one or more measuring openings or pockets 10, which are adapted to receive a portion of the material in the receptacles 2 and 3 when opposite said receptacles, and to discharge said material through the discharge openings 11 in the bottom of the body portion 1 when the rotatable parts are rotated so that the measuring openings are opposite the discharge openings. These rotatable parts may each be provided with one pocket or a plurality of pockets. The powdered material in the receptacle 3 is liable to pack, so that it will not freely pass into the measuring opening 80 or pocket 10, and some means is provided for preventing this packing and insuring the passage of equal amounts into these measuring openings when the device is being used. As herein shown, I provide an 85 agitating piece or disk 12, adapted to be located at the bottom of the receptacle 3. The bottom of this receptacle is preferably beveled, as shown at 13, and the piece or disk 12 is also beveled, and its diameter is 90 shorter than the diameter of the receptacle, so that it may be freely moved back and forth across the receptacle above the discharge opening through which the powdered material passes into the measuring 95 opening 10. The agitating piece 12 is preferably provided with a plurality of openings 14 and a centrally located opening 15. An agitating spring 16 passes through one of the openings in the part 12, preferably 100 the opening 15, the spring preferably projecting through the part 12 so that its end projects beyond the wall of the opening 9 and a short way into one of the measuring 105 openings 10. When the rotating part 7 is rotated, the spring 16 will engage the side of the measuring opening 10 and be moved to one side, carrying the agitating part 12 with it, and as the rotatable part 9 is further rotated will be suddenly released and 110 spring back, carrying the agitating piece 12 back with it. It will thus be seen that the

agitating part 12 is thus given a rapid movement, thereby agitating the powdered material at each movement of the part 7 so as to prevent packing thereof and so as to insure the proper amount of powdered material being discharged into the measuring opening 10. The spring 16 is preferably held to one side by engagement with the portion of the rotatable part 7 between the openings or pockets 10 while the rotatable part 7 is being rotated, until the next measuring opening comes beneath the receptacle, whereupon the spring is released and it then flies back, thus agitating the material just when the measuring opening is receiving such material. In view of the fact that the agitating piece 12 must be at the bottom of the receptacle, it will be seen that it and the spring 16 must be in position before the powder is inserted, and that these parts must not be disturbed by removing the cover 4 to insert the powder. In the construction herein shown the spring 16 is provided at the top with an engaging part 17, which engages the wall of the receptacle. I prefer to form the agitating spring 16 of a spring wire and to form the engaging part 17 integral with it by bending this wire so as to form the piece 18. The engaging part 17 may be formed by a loop produced by bending the wire as shown in Figs. 2 and 4. The piece 18 permits the spring 16 to be located near the middle of the receptacle. I also prefer to provide a groove 19, the engaging part 17 being within this groove so that it will be held against downward movement. It will thus be seen that the cover 4 may be removed without disturbing the spring and agitating piece 12, and that said cover, when placed in position, will prevent the upward movement of the engaging part 17 and hence the spring 16. I prefer to provide some simple means for preventing the rotatable parts 6 and 7 from being withdrawn from the body portion 1. In the construction shown I secure this result by fastening to the ends of said rotatable parts the spring pieces 20, made of metal or the like which tends to resist bending and which spring back to their original positions when bent, said spring pieces being removably fastened in position by means of fastening devices 21. The size of the measuring openings 10 may be permanent, as shown in Fig. 7, or they may be adjustable so that varying amounts of material may be measured and discharged thereby. As shown in Fig. 3, these measuring openings are provided with adjustable bottoms 22, said adjustable bottoms having screw threads which engage screw threads in the openings or pockets 10. The adjustable bottoms are preferably provided with means by which they may be rotated to vary their position in the openings or pockets 10 in

order to vary the amount of material contained in such pockets. As herein shown, these adjustable bottoms are provided with grooves 23 for a suitable instrument such as a screw driver, so that they may be rotated to move them in or out to vary the size of the openings or pockets 10. 70

In the specification and claims I have used the word "groove" to indicate the space into which the loop 17 is received, and 75 I use this term without limitation as to width of the groove.

I claim:

1. A device for measuring materials for tooth fillings, comprising a body portion, a 80 receptacle therein adapted to receive powdered material, a rotatable part mounted in an opening in the body portion and located beneath said receptacle, said rotatable part provided with a measuring opening 85 adapted to communicate with the receptacle when the rotatable part is in a predetermined position, an agitating piece in the bottom of said receptacle, adapted to be moved back and forth there-across, an agitating spring projecting through said agitating piece, the end thereof engaged by said rotatable part, the upper end of said spring bent into the form of a loop engaging the wall of said receptacle so as to be 90 held in place. 95

2. A device for measuring materials for tooth fillings, comprising a body portion, a receptacle therein adapted to receive powdered material, said receptacle having a discharge opening, a rotatable part for controlling said discharge opening, said rotatable part provided with a measuring opening to receive a measured quantity of said powdered material, an agitating piece in 100 the bottom of said receptacle, and an agitating spring projecting through said agitating piece, said agitating spring removably connected with said body portion. 105

3. A device for measuring materials for tooth fillings, comprising a body portion, a receptacle therein, adapted to receive powdered material, said receptacle provided with a discharge opening, a measuring device associated with said discharge opening 110 for receiving measured quantities of said powdered material, a laterally moving agitating piece above said discharge opening, loosely mounted in said receptacle, a spring in said receptacle connected with said agitating piece, said spring removably engaging said receptacle at its upper end, and a removable cover for said receptacle, separate from said spring, means for moving said agitating piece laterally in one direction, said spring moving it in the opposite direction. 115 120

4. A device for measuring materials for tooth fillings, comprising a body portion, a receptacle therein, adapted to receive 130

powdered material, said receptacle provided with a discharge opening, a measuring device associated with said discharge opening for receiving measured quantities of said powdered material, an agitating piece above said discharge opening, loosely mounted in said receptacle, a spring in said receptacle connected with said agitating piece, said spring provided at its upper end with a loop which engages the inner wall of the receptacle, and means for preventing said loop from moving up or down when the spring is in its operative position.

5. A device for measuring materials for tooth fillings comprising a body portion, a receptacle therein adapted to receive powdered material and provided with a discharge opening, a rotatable part mounted in said body portion, said rotatable part

provided with a measuring opening adapted to communicate with said receptacle when the rotatable part is in a predetermined position, an agitating device near said discharge opening, a spring engaging said agitating device, the upper end of said spring having a laterally bent part, a loop with which said laterally bent part is connected, the inner wall of the receptacle provided with a groove into which said loop is received.
